UNITED STATES PATENT OFFICE

92,050

DESIGN FOR A VEHICLE TIRE

Giuseppe Vidale, Milan, Italy, assignor to Societa
Italiana Pirelli, Milan, Italy, a corporation of Italy

Application July 12, 1933, Serial No. 48,700

Term of patent 3½ years

To all whom it may concern:

Be it known that I, GIUSEPPE VIDALE, an Italian subject, residing at Milan, Italy, have invented a new, original, and ornamental Design for Vehicle Tires, of which the following is a specification, reference being had to the accompanying drawing, forming part thereof.

The design of the tread adjacent the side walls of the tire is identical on both sides.

I claim:

The ornamental design for a vehicle tire, as shown and described.

GIUSEPPE VIDALE.
